UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

WEATHER-STRIP.

1,256,052

Specification of Letters Patent. Patented Feb. 12, 1918.

Application filed October 16, 1915. Serial No. 56,185.

To all whom it may concern:

Be it known that I, HARRY H. SCHROYER, a citizen of the United States, and a resident of the city of Chicago, in the county of Cook and State of Illinois, have invented certain new and useful Improvements in Weather-Strips; and I do hereby declare that the following is a full, clear, and exact description of the same, reference being had to the accompanying drawings, and to the numerals of reference marked thereon, which form a part of this specification.

It is an important object of this invention to construct a weather strip comprising a piece of resilient metal folded over to receive a strip of fabric engaged therein and with the outer margin of the metal strip angled outwardly and slotted to afford a plurality of flexible reinforcing means for the fabric.

It is an object of this invention to construct a simple and improved type of weather strip particularly adapted for use upon car windows and of flexible nature acting to spring inwardly beyond the normal plane of engagement with the sash when the sash is moved from closed to open position and to bear closely upon the surface of the same to seal the same when the same is moved into closed position in the casing.

On the drawings:

Figure 1 is a fragmentary central vertical section taken through a window casing illustrating a weather strip embodying the principles of my invention associated therewith.

Fig. 2 is a section taken on line 2--2 of Fig. 1.

Fig. 3 is a bottom plan view similar to Fig. 2, illustrating the position assumed by the weather stripping means when the sash is moved into an open position.

Fig. 4 is an elevational view of the weather strip shown detached from the casing.

Fig. 5 is a detail section taken on line 5--5 of Fig. 4.

Fig. 6 is a fragmentary exterior elevation of a window sash and frame of different construction equipped with a modified form of my invention.

Fig. 7 is a section on line 7--7 of Fig. 6.

Fig. 8 is a sectional detail of the weather strip when detached from the sash.

Fig. 9 is a sectional view partly in elevation through the lower end of a window sash showing my invention mounted to seal against the sill of the sash frame.

As shown on the drawings:

The reference numeral 1, indicates as a whole the frame or casing of a window having an inner stop 2, with a curtain groove 3, therein, and an outer stop 4, with a sash denoted by the reference numeral 5, slideable in the groove between said inner and outer stops. Secured upon the surface of the outer stop 4, is a weather strip comprising a strip of metal 6, with one margin thereof folded around in parallel relation as denoted by the reference numeral 7, affording a long recess in which is inserted one margin of a strip of fabric 8. The body of the metal strip 6, as well as the folded margin 7, thereof, is punched at a plurality of points as indicated by the reference numeral 9, to indent the metal into engagement with the margin of the fabric strip to insure positive engagement thereof within the metal strip. The other margin of said metal strip is bent at an angle as clearly shown in Fig. 5, and is provided with a number of slots 10, at points therealong affording substantially a plurality of independent resilient members or leaf springs 11, which act as a reinforcement for the fabric 8, when the same is bent outwardly due to contact with the surface of the sash 5. The weather strip is held upon the casing by means of screws 12, as shown in Fig. 1, and as shown in Figs. 2 and 3, the outer surface of the sash 5, may be provided with a shallow groove or recess 13, extending therealong adapted to receive the margin of the fabric 8, projected thereinto.

In the modified form of device shown in Figs. 6, 7 and 8, I have shown the weather strip as consisting of a strip of metal 14, with one margin thereof folded over upon the margin of a piece of fabric 15, as designated by the reference numeral 16, and with the other margin normally angled inwardly and slotted to afford a plurality of resilient members or leaf springs 17. The strip with its associated fabric sealing means is attached by means of screws 18, to the outer surface of the stile 19, of a window sash extending over a longitudinal groove or recess therein into which projects a tongue or stop 20, integral with a portion of the window frame and a member 21, is secured to the window frame and holds the tongue 20, from springing inwardly.

In Fig. 9, I have shown the weather strip of Figs. 6, 7, and 8 connected on the under surface of the bottom rail of the sash 5, of

Figs. 1 to 5, to bear upon the sill of the frame when the sash is closed.

The operation is as follows:

- When the device is in use it is attached 5 upon the stop 4 of the window casing in a position wherein the fabric 8, bears in the groove or recess 13, provided on the sash 5, and the fabric is reinforced and held thrust closely against said sash by the reinforcement afforded by the resilient members 11, 10 formed on said strip in which the fabric is secured. As a result, when the sash is raised or moved into open position, the fabric portion 8, springs inwardly below the 15 sash beyond the normal plane of contact with the sash as clearly shown in Fig. 3, but, however, again springing outwardly into close contact with the wall of the recess 13, when the sash is again closed.
- 20 In the modified form of device illustrated in Figs. 6 to 8 inclusive, the resilient weather strip element bearing upon the tongue 20, interfitting with the sash, thrusts the entire sliding sash outwardly in close contact 25 with the inner surface of the tongue 20, thus holding the sash snugly against rattling in the frame.

Due to the fact that in all of the constructions shown, the reinforcement consists of 30 a plurality of resilient members, it is evident that the same is capable of readily adapting itself to irregularities of construction or other inaccuracies such as occur on the surface of contact with the sash or frame, so that a close seal of the weather strip with the sash is afforded at all times.

I am aware that various details of construction may be varied through a wide range without departing from the principles of this invention, and I therefore do 40 not purpose limiting the patent granted otherwise than necessitated by the prior art.

I claim as my invention:

1. A weather strip of the class described 45 comprising a metal strip, one margin thereof folded inwardly to afford a recess, a strip of fabric engaged in said recess, and the other margin of said strip bent outwardly and slotted to form a plurality of leaf 50 springs affording a plurality of resilient reinforcing members for the projecting margin of said fabric strip.

2. A device of the class described comprising a metal strip, a strip of fabric engaged 55 therewith and a plurality of resilient leaf spring members integral with said metal strip to reinforce the projecting margin of the fabric strip.

3. In a device of the class described a 60 metal strip, one margin thereof folded inwardly to afford a recess, a strip of fabric

engaged in said recess, said metal strip and inturned margin thereof punched from the exterior surface to indent the metal into engagement with the fabric strip to retain the 65 same engaged therein, and a plurality of angled resilient leaf spring reinforcement members integral with said strip to reinforce the projecting margin of said fabric strip.

4. A weather strip of the class described comprising a strip of metal, a piece of fabric, one margin of said metal bent over to retain the strip of fabric associated with 70 said strip of metal, the other margin of 75 said strip of metal angled outwardly and having a plurality of slots therein extending through the outer edge affording a plurality of resilient reinforcement leaf spring members for the projecting margin of said 80 strip of fabric.

5. The combination with a window frame and its sash, of weather stripping means connected therebetween comprising a strip of fabric, a plurality of resilient members 85 associated therewith to thrust the same into sealing relation and a tongue connected to the frame and interfitting with the sash against which the sash is thrust by the resilient members.

6. The combination with a window frame and its sash, of a tongue on the window frame, weather stripping means secured upon the sash and disposed over a groove therein in which the margin of said tongue 95 extends, a member secured to the frame bearing against the inner surface of said tongue to hold the tongue from springing inwardly, and a plurality of resilient elements forming a part of said weather strip- 100 pping means acting to draw the sash firmly against the tongue.

7. The combination with a window frame and its sash having a longitudinal groove in the stiles thereof, of a tongue on the 105 window frame fitting in the groove in said sash, a member secured to the frame and bearing against the inner surface of said tongue to hold the same from being thrust inwardly and weather stripping means of 110 resilient nature mounted on the sash overlapping the groove therein and bearing against the outer surface of said tongue to draw the sash closely against the tongue to seal the sash in the frame.

In testimony whereof I have hereunto 115 subscribed my name in the presence of two subscribing witnesses.

HARRY H. SCHROYER.
